(57) **CLAIM**

The ornamental design for a speakerphone, as shown and described.

DESCRIPTION

FIG. 1 is a front, left, top side perspective view of a speakerphone, showing a first embodiment of the claimed design;

FIG. 2 is a top plan view thereof;

FIG. 3 is a right side elevational view thereof;

FIG. 4 is a left side elevational view thereof;

FIG. 5 is a front side elevational view thereof;

FIG. 6 is a rear side elevational view thereof;

FIG. 7 is a bottom plan view thereof;

FIG. 8 is a perspective view of a speakerphone, showing a second embodiment of my new design;

FIG. 9 is a top plan view thereof;

FIG. 10 is a right side elevational view thereof;

FIG. 11 is a left side elevational view thereof;

FIG. 11 is a rear elevational view of thereof;

FIG. 12 is a bottom plan view of thereof; wherein a front side elevational thereof view is identical to FIG. 5 and a rear side elevational view thereof is identical to FIG. 6;

FIG. 13 is a perspective view of a speakerphone, showing a third embodiment of my new design;

FIG. 14 is a top plan view thereof;

FIG. 15 is a right side elevational view thereof;

FIG. 16 is a front side elevational view thereof;

FIG. 17 is a rear side elevational view thereof; wherein a left side elevational view thereof is identical to FIG. 4; wherein a bottom plan view thereof is identical to FIG. 7;

FIG. 18 is a perspective view of a speakerphone, showing a fourth embodiment of my new design;

FIG. 19 is a top plan view thereof; and,

FIG. 20 is right side elevational view thereof; wherein a left side elevational view thereof is identical to FIG. 11; wherein a front side elevational view thereof is identical to FIG. 16;

(Continued)

wherein a rear side elevational view thereof is identical to FIG. 17; and wherein a bottom plan view thereof is identical to FIG. 12.

The evenly dashed lines shown in the drawings depict portions of the speakerphone that form no part of the claimed design. The dash-dot lines shown in the drawings show a symbolic break in length. Any portions of the article between the dash-dot lines form no part of the claimed design.

1 Claim, 14 Drawing Sheets
